(57) **CLAIM**

The ornamental design for a set of bed sheets, as shown and described.

DESCRIPTION

FIG. 1 is a right side elevational view of the bed sheet system showing my new design, the left side elevational view and the right side elevational view being identical;

FIG. 2 is a front elevational view, the rear elevational view and the front elevational view being identical;

FIG. 3 is top plan view.

FIG. 4 is a bottom plan view of the bed sheet system. The straps are shown in a broken line indicating that the straps and buckles are not part of the claim and are shown for environmental purposes only; and,

FIG. 5 is an exploded view of the top sheet and the bottom sheet, demonstrating how the top sheet is aligned with the bottom sheet.
